UNITED STATES PATENT OFFICE.

E. WILSON FARNHAM, OF CHICAGO, ILLINOIS, ASSIGNOR TO THOMAS A. STRAYER, OF SAME PLACE.

PENMAN'S ARM-REST.

SPECIFICATION forming part of Letters Patent No. 268,474, dated December 5, 1882.

Application filed June 26, 1882. (No model.)

To all whom it may concern:

Be it known that I, E. WILSON FARNHAM, of Chicago, in the county of Cook and State of Illinois, have invented certain new and useful 5 Improvements in Penmen's Arm-Rests; and I do hereby declare that the following is a full, clear, and exact description of the invention, which will enable others skilled in the art to which it appertains to make and use the same, 10 reference being had to the accompanying drawings, and the letters of reference marked thereon, which form a part of this specification.

My invention relates to that class the object of which is to afford a rest for the arm when 15 writing on a surface above that upon which the material to be written on rests. It is a substitute for the ordinary arm-rests having a transverse ledge or raised portion on one end of a thin board, which latter is inserted be- 20 tween the leaves of the book, thus running the risk of injuring the same by tearing the leaves and affording a very precarious rest for the arm. This I accomplish by means of two boards of rectangular or other suitable shape, 25 one of which rests on the table or desk, having one end slightly extended to be pushed under the book, the other being of the same shape, minus the extension, and placed immediately above the bottom or lower board. These boards 30 are connected at or near four corners by jointed links whose angles tend inward toward the line indicating the center of length of said boards, and which are so constructed and ar- 35 ranged that the upper board or arm-rest proper can be raised to any desired elevation within the throw of said jointed links or inclined toward either end, as suits the convenience of the user, and maintained in such position, substantially as described in the following specification, and 40 set forth or illustrated in the drawings, in which—

Figure 1 is a side elevation. Fig. 2 is a plan view with the top board removed.

A and B represent the top and bottom boards, 45 respectively. The bottom board, B, is intended to rest upon the desk or other support upon which the writing material or book is placed, and has an extension, a, on one end in the direction of its length, which is intended to be 50 inserted under the cover of the book, so as to

keep the device from moving. This extension, though, may be dispensed with, and U-shaped spring-grasps may be secured to the end of the board, so as to pinch the cover of the book, in the stead of the same; or both may be dis- 55 pensed with, if desired, as it is conceived the weight of the writer's arm would hold it stationary. The upper board or arm-rest proper, A, is of the same shape and dimensions, minus the extension a, as the lower board. These 60 boards are strengthened by the transverse strips a' a' near the ends of the same. Passing under these strips a', near their ends, and secured to the under side of the top board, A, and the upper side of the bottom board, B, by 65 the same, are straps b b. These straps, it will be perceived, are located near the four corners of each board, and their inner ends are formed into knuckles to receive the knuckles of the knee or jointed links C C O' C', connecting the 70 boards A and B. These links are so arranged that the angles of the two joints near one end face or operate toward the two links near the other end, thus securing a vertical motion, if desired. The upper bars, c c, of two of the 75 jointed links, C' C'—one on either side of the device near corners diagonally opposite to each other—have extending in the direction of their length, and in a straight line to the lower board, the arms or extensions d d, which may 80 be made in one piece with or securely fastened to the bars c. These arms d are tapered transversely at their lower ends to form a knife-edge, which engages with the racks D D on the upper surface of the lower board, (see Fig. 85 1,) by means of which the arm-rest proper may be maintained at any desired elevation within the throw of the joints C' C.

It will be observed from the construction above described that the upper board or arm- 90 rest may be inclined in the direction of its length or toward its ends by adjusting the arm, at the end to be elevated, higher or toward the inner end of the rack, as suits the convenience of the writer. If desired, the lower 95 board could be dispensed with and an open metal frame be used in its stead, and wire could be conveniently used to form the jointed links, so as to simplify device.

By the above means I obtain a simple, cheap, 100

and convenient arm-rest, which would be an acquisition to the ordinary desk material, and avoid the use and abuse of nondescript material in the effort to procure a suitable elevation and incline of the arm.

5 What I claim, therefore, and wish to secure by Letters Patent, is—

1. The combination of the boards, the jointed connecting-links, the extensions, and means, substantially as described, with which said extensions engage, whereby the upper board is adapted to be raised vertically, or be inclined toward either end and be maintained in its adjusted position, as and for the purpose set forth.

2. An arm-rest consisting of boards A and 15 B, straps b, jointed links C C, jointed links C' C', having extensions d d, and racks D D, arranged and connected as hereinbefore set forth, substantially as and for the purpose described.

In testimony that I claim the foregoing as 20 my own I hereunto affix my signature in the presence of two witnesses.

E. WILSON FARNHAM.
